Williamson & Holmes

UNITED STATES PATENT OFFICE.

JOHN H. HOLMES, OF ANOKA, MINNESOTA.

WINCH.

1,353,238.

Specification of Letters Patent. Patented Sept. 21, 1920.

Application filed October 13, 1919. Serial No. 330,322.

To all whom it may concern:

Be it known that I, JOHN H. HOLMES, a citizen of the United States, residing at Anoka, in the county of Anoka and State of Minnesota, have invented certain new and useful Improvements in Winches; and I do hereby declare the following to be a full, clear, and exact description of the invention, such as will enable others skilled in the art 10 to which it appertains to make and use the same.

My invention relates to that class of mechanism generally known as a winch, and has for its object to provide an improved driving mechanism therefor.

Especially, the invention has for its object to provide a driving mechanism which will transmit power to the winch drum at very greatly reduced speed and correspondingly increased power, and which will be self-locking so that it will not be reversely driven to unwind the cable under the force applied to the drum, even when the driving power is disconnected from the winch.

These objects are accomplished by extremely simple and efficient means in accordance with my invention which is illustrated in the accompanying drawings wherein like characters indicate like parts throughout the several views.

Referring to the drawings:

Figure 1 is a plan view of the improved winch with some parts broken away and some parts sectioned; and

Fig. 2 is a vertical section taken on the line 2-2 of Fig. 1.

The winch itself may be of any suitable construction, and comprises a drum and a suitable framework upon which the drum is mounted. The framework, as shown, is made up of a top plate 3, bottom plate 4, and connecting posts 5. The drum 6, upon which the cable 7 is wound, has a square axial passage that fits a square shaft 8 passed axially therethrough and having a round lower end 8^a journaled in the bottom plate 4. The square shaft projects at its upper end above the upper end of the drum 6 and through the top plate 3, and fits within a square seat formed in a hub 9 of a large spur gear 10. Hub 9, it will be noted, is journaled in and extends through the central portion of top plate 3 and the reduced upper end 8^b of shaft 8 is provided with a nut 11 and washer 12 which detachably

holds the gear 10 positioned on the upper end of said shaft 8.

Axial or central spur gear 10 meshes with a plurality, as shown, three circumferentially spaced spur pinions 13 journaled on studs 14 fixed at their lower ends within top plate 3 and provided at their upper ends with nuts 15 that detachably hold the pinions in working position, free to rotate on the respective studs.

Meshing with the several pinions 13 and entirely surrounding the same is a larger annular internal spur gear 16 that is provided with external worm gear teeth 17. On its inner face, above and below its internal teeth, ring gear 16 is provided with inwardly projecting retaining flanges 16^a that embraces the outer teeth of the several pinions 13 and run against upper and lower hubs 13^a of said pinions, so that the said ring gear is not only held for true rotary motion around the axis of shaft 8 and the co-incident axis of central gear 10, but has a rolling engagement with the hubs of the said pinions.

The external worm gear teeth 17 of the ring gear 16 meshes with a worm 18 on a shaft 19 journaled in suitable bearings 20 on the top plate 3. This shaft 19, while free to rotate, is held against endwise movements by collars 21 on said shaft that engage the bearings 20 and resist endwise thrust on said shaft 19. At one end, shaft 19 is provided with a pulley 22, over which runs a power driven belt 23 driven from any suitable source, not shown. In practice, the framework of the winch may be suitably anchored on a truck, and belt 23 can be driven from an engine carried on the same truck, but the manner of mounting and driving the winch may be varied at will, so far as this invention is concerned.

As is evident, under power applied to shaft 19, rotary motion will be applied to the drum 6 through the gears and pinions described at relatively very slow speed and correspondingly great power.

In the construction described, the gear mechanism may be quickly removed or applied. When the nuts 11 and 15 are removed, gear 10 may be readily lifted off from the upper end of shaft 8 and the pinions 13 from the studs 14 and the ring gears 16 will come off with the said central gear and pinions.

The engagement with the worm and worm gear, as is evident, will lock the winch in any position of the drum so that the strain on the cable cannot unwind the cable from the drum.

What I claim is:

1. The combination with a winch including a framework and a drum mounted therein, of a central gear connected to said drum, pinions journaled on the winch frame and meshing with said central gear, an annular internal ring gear surrounding and meshing with said pinions and provided with external worm gear teeth, a shaft journaled on the winch frame and provided with a worm engaging the external worm gear teeth of said ring gear, said pinions having hubs on which said annular gear runs with rolling engagement.
2. The combination with a winch including a framework and a drum mounted therein, of a central gear connected to said drum, pinions journaled on the winch frame and meshing with said central gear, an annular internal ring gear surrounding and meshing with said pinions and provided

with external worm gear teeth, a shaft journaled on the winch frame and provided with a worm engaging the external worm gear teeth of said ring gear, said ring gear having inner and outer annular inwardly projecting retaining flanges that embrace the outer teeth of said pinions, and the said pinions having inner and outer hubs on which the said retaining flanges run with rolling engagement.

3. The combination with a winch including a framework and a drum mounted therein, of a central gear connected to said drum, pinions journaled on the winch frame and meshing with said central gear, an annular internal ring gear surrounding and meshing with said pinions and provided with external worm gear teeth, a shaft journaled on the winch frame and provided with a worm engaging the external worm gear teeth of said ring gear, the said central gear being detachable from said drum and said pinions being detachable from their mountings on said frame.

In testimony whereof I affix my signature.
JOHN H. HOLMES.
